UNITED STATES PATENT OFFICE.

VERNON W. NORTHRUP, OF HURLOCK, MARYLAND, ASSIGNOR TO THE PETROLEUM HYDROGENATION COMPANY OF AMERICA, INCORPORATED, OF WILMINGTON, DELAWARE, A CORPORATION OF DELAWARE.

PROCESS AND APPARATUS FOR THE CONVERSION OF HEAVY PETROLEUM OILS INTO LIGHTER OILS.

Application filed November 20, 1924, Serial No. 751,171. Renewed February 8, 1927.

This invention relates to processes for the conversion of heavier into lighter hydrocarbons in the same series, and involves the step of hydrogenation by subjecting an approximately correctly proportioned mixture of the vapors of such heavier or higher boiling petroleum oils and a source of hydrogen to an electric field and then to catalytic action, thereby fixing the reaction mass into a new, permanent compound or compounds of the nature of lower boiling petroleum oils, as hereinafter set forth.

Any crude petroleum oil as it comes from the ground is a complex of numerous hydrocarbons, very nearly alike as regards percentages of hydrogen and carbon, but with widely different boiling points, and in ordinary refining these various hydrocarbons are separated by distillation into varying groups or "cuts" of fractions boiling within certain ranges, commercially known as gasoline, kerosene, gas-oil, fuel oil, etc. Of these cuts, gasoline is at the present time the most valuable, and for this reason various methods have been devised to "crack" the heavier cuts into the lighter ones.

"Cracking" processes, in the main, have consisted of some method of subjecting these heavy cuts, either in the vapor or liquid phase, to an amount of heat and pressure sufficient for their decomposition, thus liberating the hydrogen in the form of a non-condensable gas, and the carbon in the form of still higher boiling oils or coke. The gasoline yields in these "cracking" processes are poor as there is not enough hydrogen present in any petroleum oil to give in this way any large percentage of gasoline, as the gases which are necessarily formed through this destructive distillation are much richer in hydrogen than gasoline, and the oils remaining in the still after cracking have nearly as much hydrogen as gasoline, 20% of gasoline from most of the cracking processes being considered a good yield.

Excellent efficiency and very high yields of gasoline result from the treatment of the heavy petroleum oil according to my invention.

As is well known, there is but a small percentage more of hydrogen in gasoline than in kerosene or fuel oil. For instance, present

day gasoline is probably composed mostly of heptane (C_7H_{16}) which contains but about one-half of one percent (0.51) more hydrogen than kerosene (decane, $C_{10}H_{22}$). The addition of only a very small percentage of hydrogen is, therefore, theoretically necessary to convert the heavier fractions of crude oil into lighter and lower boiling point compounds.

For supplying this hydrogen, I may use any source thereof, but I prefer either hydrogen itself or natural gas which usually consists principally of methane (CH_4). Examples of the sum total of the reactions taking place are probably as set forth in the following equations, but it is to be understood that my invention is not to be limited thereby:

Theoretically, my invention seems to be based on the fact that petroleum oils contain substances which behave like radium and which apparently ionize the vapors of petroleum oils and impart to them a high conductivity. Free ions seem to be present to a large extent in both the lighter and heavier petroleum vapors, rendering them exceedingly susceptible to electrical influences and whereby they are converted into charged ions, and the electrical field to which I subject the vapors in my process is such as apparently to have an influence upon the electrons and ions, atoms and molecules, present in the vapors of the higher boiling oils and of the hydrogen-rich gas, causing some form of rearrangement of particles and charges, and is, according to this theory, sufficient to cause changes, such, for example, as electronic interchange between the ions in the higher boiling petroleum vapors and the hydrogen-rich gas to form the constituents into new groups and to influence the molecular structure and rearrangement of the atoms in the molecules, whereby a reaction mass is produced, which is very easily catalyzed into permanent compounds of the na-

ture of gasoline, the catalyst being heated to a temperature below which ordinary cracking or destructive distillation takes place.

Referring to the drawing, the figure is a partially diagrammatic side view, partly in elevation and partly in section, of my apparatus.

I provide a still A which is suitably heated to convert heavier petroleum hydrocarbons therein into vapors, which vapors rise up through the tube B connected to the still. The tube B has an opening in the top thereof in which an insulator E is tightly fitted, which supports an electrode wire D substantially centrally of the tube B, this electrode being held taut centrally of the tube by a bob T of non-conducting material at the lower free end thereof, and such bob is preferably fluted to permit the free passage of gas. An inlet pipe C surrounds the lower end of the tube B and is connected therewith by a series of openings C', by means of which hydrogen-rich gas, such as hydrogen, methane, natural gas, etc., is led into the lower end of the tube B to mix with the hydrocarbon vapors therein, means being provided such as the valve C'' for properly controlling the proportions of hydrogen-rich gas. A conducting member from which the wire electrode D depends passes through the insulator E and one terminal of a source of high tension alternating electric current is connected therewith as at F, the other terminal from such source of current being connected to the tube B as at G.

A tube H conducts the electrified vapors and gases to a catalyzing chamber consisting of the tube I surrounded by the lagging cover K, inside of which any suitable means is provided for heating the tube, such as a gas or oil flame, or a resistance coiled about the tube I. A tube J having a corrugated outer surface is provided within the tube I, the catalytic surfaces of which cause the vapor-gas mixture to travel throughout the length of the catalyzer in a thin annular stream, the functions of the corrugations being to cause swirling movements in this stream in order to effect maximum contact of the gas-vapor mixture with the catalyzer surface.

The opposing surfaces of the tubes I and J may be composed of or coated with catalytic material, such as nickel, cobalt, palladium, aluminum, iron, etc., or mixtures thereof, a very efficient catalyst being nickel containing about 5% of iron and 5% of aluminum, such catalytic surfaces being rendered more active by the heating means aforesaid.

The catalyzed mixture then passes by means of the pipe L to the dephlegmating tower or column M which is of the usual inverted cup type, and from this they pass through the pipe N to the top of the cooler

O of the usual tube type. A cooling medium, preferably a high boiling petroleum oil, is maintained at a temperature of about 200° F. to 400° F. and is circulated around the exterior of pipes U of the cooler O by means of the inlet and outlet pipes O'. This will effect sufficient cooling but will nevertheless permit the gasoline-like compounds produced to pass out through the pipe Q in the vapor state, the temperatures of the cooler O and the column M being thereby suitably maintained for this purpose. The bottom ends of the pipes U lead to a chamber in the bottom of the cooler which is connected by the pipe Q to a condenser Q' which in turn is connected by pipe R to the tail house and finished product storage tanks, which are not shown. A trap P connects the bottom chamber of the cooler O with the top of the tower M.

The vapors of higher boiling points are condensed in the column M and pass to the bottom thereof as is usual in such columns and any liquid passing into such column through the pipe L does not rise therethrough. Furthermore, vapors condensed in the cooler O, after passing through the trap P, pass gradually downwardly through the column M to the bottom thereof; and all the liquids which are not of gasoline boiling points and which pass to the bottom of the column M flow therefrom through pipe S back to the still A.

Various types of electric treatment for the conversion of petroleum hydrocarbons have already been proposed, for example, to impress an electric current of high density or high frequency, upon petroleum vapors or mixtures of petroleum vapors and a hydrogen-rich gas, to effect by the use of such high density current, or such high frequency current, alone, a cracking action, without, however, combining the same with catalytic action; or to treat a mixture of heavier hydrocarbon vapors and a hydrogen-rich gas by subjecting the same to the effect of a catalyst which is subjected to a sparking treatment to keep it clean. In such processes, it is, however, necessary to use an electric current of such intensity that the results hoped for cannot be successfully obtained; for as a matter of fact, a current of sufficient voltage to form a brush discharge or sparking discharge is far too disruptive for the successful accomplishment of the purpose of my invention.

According to my invention, I use an electric current of a potential merely sufficient to create a strong electro-static field between the walls of the electrolyzer tube B and electrode D coaxial therewith; that is, a field merely strong enough to be efficient to ionize the particles therebetween. In practice, the tube B should be of sufficient length to thoroughly ionize the molecules present in the

mixture to be later acted upon by the catalytic material, and I have found that for eight (8) catalytic converters containing seventy-two (72) tubes each, sixteen (16) 5 catalyst tubes of an inside diameter of two and one-half (2½) inches and eighteen (18) inches long are quite effective. This effects thorough electronization of the charge of oil and hydrogen-rich gas and has been 10 found to be sufficient with from 4 to 6 pounds usual still pressure, with a clearance of about three-thirty-seconds (3½) of an inch between the ribbed tube and other catalytic tube; and when operating at temperatures 15 hereinafter specified the resulting effect is such as to produce very high yields of gasoline from fuel oil and kerosene, without the formation of any soot or carbon at any place in the system.

20 In the operation of my process heavier vapors rise from the heated oil in the still A into the tube B with which is admixed, at the bottom of tube B by means of the inlet pipe C, the proper amount of hydrogen or hydrogen-rich gas to form lighter hydrocarbons of the same series of the lighter boiling points desired later in the process. Upon this mixture of vapor and gas, an electric current is impressed sufficient 25 only to cause electrons to be set free and to move about and thoroughly ionize both molecules of the gas and those of the heavier oil vapors, thus throwing the entire mixture into ionic disorder and giving to the relative components as completely an electrostatic charge as is possible, for what is generally desired at this stage of the process is that each molecule in the entire mixture be given the correct electric charge to enable 30 all ions and molecules present to maintain equilibrium, at least temporarily, so that later in the process the catalytic material will assist the breaking up of the heavy hydrocarbons into simpler structures of 35 lower boiling points, without cracking the component molecules, it being my object to place the lighter hydrogen molecules or atoms of the other light hydrocarbon in such a state with regard to the heavy oil 40 molecules that ready adoption can take place under the effect of the catalyst to form gasoline-like material as to specific gravity and boiling points.

It is to be clearly understood that at this 45 stage of the process there has not been enough electric potential or current impressed upon the mixture up to the time of their passing from the tube B to have caused any substantial cracking or chemical change, 50 since vapors passing from the pipe H which are condensed to liquid have substantially the same composition as the mixture entering the tube B from the still A.

The thoroughly ionized mixture passes 55 into the catalytic chamber which is heated

sufficiently to render the catalytic surfaces very active and there a change takes place between the hydrogen-rich gas and the heavy hydrocarbon vapor present, compounds of gasoline-like boiling points being produced. 70 A complete change from heavier hydrocarbons to lighter hydrocarbons does not take place instantaneously throughout the mass on subjection to a catalytic surface, nor does it usually take place as a rule as a result 75 of one electric treatment followed by one catalytic treatment, and I have found that frequently from four (4) to eight (8) successive passes or combination of steps mentioned are required, the number depending to 80 some extent upon the final product desired. The vapors of the newly formed compound thus pass along into the dephlegmating tower M, and into the storage tank, as already described. 85

The number of ions produced is dependent upon the intensity of the electric discharge and varies with different crude oils, some being slightly more ionizable than others. I generally provide means for varying the potential and density of the electric current, so that it will range from about 2000 volts to 8000 volts, as desired. Two nonanes, alpha (α) and beta (β) are the primary constituents of kerosene or gasoline which 90 are composed almost wholly of paraffins C_nH_{2n+2} . I have found that with Pennsylvania oils, an intensity of 3000 volts is generally sufficient to produce the necessary 95 ionization. I have found that Oklahoma and Texas oils can be satisfactorily treated according to my invention with about 4000 volts, but the Russian and Roumanian petroleum oils containing naphthenes require 100 about 4200 to 6000 volts. 105

The temperature of the catalyst is important and it has two functions, namely to activate the catalyst and to do so at a temperature below which active cracking or complete dissociation of the heavy petroleum 110 molecules can take place. For example, for Pennsylvania oils, it is best that such temperatures be below 900° F., and for mid-continent crudes below 1000° F.

My invention comprises primarily the 115 three steps of:

(1) Obtaining a mixture in the proper proportions of high boiling point vapors and a hydrogen-rich gas;

(2) Completely ionizing said mixture, 120 that is, subjecting it to the electrical influences described; and

(3) Subjecting such electrified mass to catalytic action at a suitable temperature.

In practice I prefer to use eight (8) converters having seventy-two (72) catalytic tubes per converter on one still having a charging capacity of 250 to 500 barrels, and when hydrogenating Pennsylvania fuel oil into United States Motor Specification gas. 125 130

oline to produce the various percentages of the different boiling points and gravities, as such gases must have, I maintain the catalytic tubes of two converters at about 725° F., the next two at about 740° F., the next two at about 770° F., the next one at about 785° F., and the tubes of the final converter at about 800° F., using about five-eighths (5/8) of a cubic foot of natural gas per gallon of gasoline made. When converting Oklahoma or Texas fuel or crude oil into gasoline the temperatures of the relative converter should be maintained from 50° to 300° F. higher than for the case of Pennsylvania petroleum, and from three-fourths (3/4) to seven-eighths (7/8) of a cubic foot of natural gas should be admitted at the electrolyzers for each gallon of gasoline finally produced.

20. What I claim is:

1. The method of converting heavier hydrocarbons into lighter hydrocarbons which comprises producing a mixture of vapors of said heavier hydrocarbons and a gas having available hydrogen, passing the mixture through an electrifying zone and thereafter through a catalyzing zone which is independent of said electrifying zone.

2. The method of converting heavier hydrocarbons into lighter hydrocarbons which comprises producing a mixture of vapors of said heavier hydrocarbons and a gas having available hydrogen, passing the mixture through an ionizing zone and thereafter through a catalyzing zone which is independent of said ionizing zone.

3. The method of converting heavier hydrocarbons into lighter hydrocarbons which comprises producing a mixture of vapors of said heavier hydrocarbons and a gas having available hydrogen, electrifying the mixture without substantial cracking taking place, and then catalyzing the mixture in a zone which is independent of the electrifying locus.

4. The method of converting heavier hydrocarbons into lighter hydrocarbons which comprises producing a mixture of vapors of said heavier hydrocarbons and a gas having available hydrogen, ionizing the mixture without substantial cracking taking place, and then catalyzing the mixture in a zone which is independent of the ionizing locus.

5. The method of converting heavier hydrocarbons into lighter hydrocarbons which comprises producing a mixture of vapors of said heavier hydrocarbons and a gas having available hydrogen, electrifying the mixture without substantial cracking in one zone, and then causing permanent conversion in another zone which is independent of said first mentioned zone.

6. The method of converting heavier hydrocarbons into lighter hydrocarbons which

comprises producing a mixture of vapors of said heavier hydrocarbons and a gas having available hydrogen, ionizing the mixture without substantial cracking in one zone, and then causing permanent conversion in another zone which is independent of said first mentioned zone.

7. The method of converting heavier hydrocarbons into lighter hydrocarbons which comprises producing a mixture of vapors of said heavier hydrocarbons and a gas having available hydrogen, subjecting the same to an alternating current field of 2000 to 8000 volts in one zone, whereby the reaction mass is electrified without substantial cracking taking place, and then catalyzing in another zone which is independent of said first mentioned zone.

8. The method of converting heavier hydrocarbons into lighter hydrocarbons which comprises producing a mixture of vapors of said heavier hydrocarbons and a gas having available hydrogen, subjecting the same to an alternating current field of 2000 to 8000 volts in one zone, whereby the reaction mass is electrified without substantial cracking taking place, and then catalyzing at temperatures of about 725° F. to 1000° F. in another zone which is independent of said first mentioned zone.

9. The method of cracking heavier hydrocarbons into lighter hydrocarbons which comprises producing a mixture of vapors of said heavier hydrocarbons and a gas having available hydrogen, electrifying the mixture without substantial cracking taking place in one zone, and then catalyzing the cracking reaction in another zone which is independent of said first mentioned zone.

10. The method of cracking heavier hydrocarbons into lighter hydrocarbons which comprises producing a mixture of vapors of said heavier hydrocarbons and a gas having available hydrogen, ionizing the mixture without substantial cracking taking place in one zone, and then catalyzing the cracking reaction in another zone which is independent of said first mentioned zone.

11. In an apparatus for converting heavier oils into lighter oils, an ionizing chamber, a catalyzing chamber directly connected therewith, means to maintain the catalyst at efficient temperature, and means to separate out the desired fraction.

12. In an apparatus for converting heavier oils into lighter oils, an electrifying chamber, a catalyzing chamber directly connected therewith, means to maintain the catalyst at efficient temperature, and means to separate out the desired fraction.

13. In an apparatus for converting heavier oils into lighter oils, a still, an ionizer connected with the still, a catalyst directly connected with the ionizer, means to separate out the desired fraction, and means

to return the undesired fraction to the still.

14. In an apparatus for converting heavier oils into lighter oils, a still, an electrifier connected with the still, a catalyzer 5 directly connected with the electrifier, means to separate out the desired fraction, and means to return the undesired fraction to the still.

15. In an apparatus for converting 10 heavier oils into lighter oils, a still, an ionizer connected with the still, a catalyzer directly connected with the ionizer, means to maintain the catalyzer at efficient tempera-

ture, means to separate out the desired fraction, and means to return the undesired 15 fraction to the still.

16. In an apparatus for converting heavier oils into lighter oils, a still, an electrifier connected with the still, a catalyzer directly connected with the electrifier, means 20 to maintain the catalyzer at efficient temperature, means to separate out the desired fraction, and means to return the undesired fraction to the still.

VERNON W. NORTHRUP.
